Attorney

UNITED STATES PATENT OFFICE.

JOSEPH E. LE CERF, OF RAYMOND, WASHINGTON, ASSIGNOR OF ONE-HALF TO
ALEXANDER C. KING, OF SAN DIEGO, CALIFORNIA.

RECEPTACLE.

1,339,899.

Specification of Letters Patent. Patented May 11, 1920.

Application filed June 29, 1918. Serial No. 242,551.

To all whom it may concern:

Be it known that I, JOSEPH E. LE CERF, a citizen of the United States, residing at Raymond, in the county of Pacific and State 5 of Washington, have invented certain new and useful Improvements in Receptacles, of which the following is a specification, reference being had to the accompanying drawings.

10 This invention relates to certain improvements in receptacles and has relation more particularly to a device of this general character especially designed and adapted for use in connection with tobacco and it is an 15 object of the invention to provide a receptacle of this kind having novel and improved means whereby compartments are provided for containing tobacco and other smokers' accessories, such as matches and 20 cigarette papers.

It is also an object of the invention to provide a novel and improved device of this general character including a body consisting of two hingedly connected sections, 25 one of said sections being adapted to contain tobacco and the other of said sections serving as a closure member for the first section and wherein the second section is divided into two compartments to independently receive matches and cigarette papers.

Another object of the invention is to provide a receptacle of this general character including a compartment adapted to receive cigarette papers together with 35 means whereby such papers may be effectively retained within the compartment.

The invention consists in the details of construction and in the combination and arrangement of the several parts of my improved receptacle whereby certain important advantages are attained and the device rendered simpler, less expensive and otherwise more convenient and advantageous for use, as will be hereinafter more 45 fully set forth.

The novel features of my invention will hereinafter be definitely claimed.

In order that my invention may be the better understood, I will now proceed to 50 describe the same with reference to the accompanying drawings, wherein:

Figure 1 is a view partly in side elevation and partly in section of a receptacle constructed in accordance with an embodiment of my invention;

Fig. 2 is a view in end elevation of my improved receptacle as herein disclosed;

Fig. 3 is a longitudinal transverse sectional view taken through my improved receptacle as herein embodied with the sections of the body portion in open position and the cover of one of the sections also in open position; and

Fig. 4 is a fragmentary longitudinal view taken through my improved receptacle and 65 at right angles to the line of section of Fig. 3, said figure also illustrating a slightly modified construction.

As disclosed in the accompanying drawings B denotes a body formed of suitable 70 material and of a size and configuration to permit its ready insertion within a pocket. The body B comprises two sections 1 and 2 hingedly connected for relative movement. The section 1 is materially larger than the 75 section 2 and has its outer end closed as at 3 and said section 1 is adapted to contain tobacco. The section 2 is open at its opposite ends and is adapted to receive the open end portion of the section 1 and the 80 overlying marginal portions or corresponding side faces of the sections 1 and 2 are provided with the intermeshing knuckles 4 through which passes a pintle 5 whereby said sections 1 and 2 are hingedly connected.

The section 2 is intersected by the partition 6 disposed transversely of the body B and which provides the compartments *a* and *b*. The outer compartment *a* is adapted to 90 contain matches while the inner compartment *b* is adapted to contain cigarette papers. The outer end of the section 2 or the open face of the compartment *a* is adapted to be closed by the hinged cover 7. 95

Intersecting the compartment *b* and extending in a direction longitudinally of the partition 6 is a rod or wire 8 secured at one extremity to an end wall of the compartment *b*. The opposite extremity of the rod or 100 wire 8 is free so that said rod or wire may be readily flexed to permit the insertion of cigarette papers between the rod or wire 8 and the partition 6 so that said papers will be effectively retained within the compartment *b* yet readily removed therefrom when required.

While it is preferred that one extremity of the rod or wire 8 be free, a rod or wire 8^a may be employed as illustrated in Fig. 4 110

wherein the opposite extremities of said rod or wire are anchored to the end walls of the compartment b' of the section 2^a .

From the foregoing description, it is thought to be obvious that a receptacle constructed in accordance with my invention is particularly well adapted for use by reason of the convenience and facility with which it may be assembled and operated and 10 it will also be obvious that my invention is susceptible of some change and modification without departing from the principles and spirit thereof and for this reason I do not wish to be understood as limiting myself 15 to the precise arrangement and formation of the several parts herein shown in carrying out my invention in practice except as hereinafter claimed.

I claim:

20 1. A receptacle of the class described comprising in combination, a hollow body divided transversely into two sections, said sections being hingedly connected, the outer end of one of the sections being closed and 25 the opposite ends of the second section being open, a partition intersecting the second

section substantially at its center and affording an inner compartment and an outer compartment, a cover coacting with the open face of the outer compartment, and a rod 30 intersecting the inner compartment, said rod extending longitudinally of the partition.

2. A receptacle of the class described comprising, in combination, a hollow body divided transversely into two sections, said sections being hingedly connected, the outer end of one of the sections being closed and the opposite ends of the second section being open, a partition intersecting the second section and affording an inner compartment 35 and an outer compartment, a cover coacting with the open face of the outer compartment, and a flexible rod intersecting the inner compartment, one end of the rod being 40 free.

In testimony whereof I hereunto affix my signature in the presence of two witnesses.

JOSEPH E. LE CERF.

Witnesses:

GEO. W. ANDERSON,
F. P. GANN.
